UNITED STATES PATENT OFFICE.

WILLIAM J. HULFORD AND FREDERICK TILLOTSON, OF LAWRENCE,
MASSACHUSETTS.

PICKER-STAFF CHECK FOR LOOMS.

SPECIFICATION forming part of Letters Patent No. 374,835, dated December 13, 1887.

Application filed May 4, 1887. Serial No. 237,082. (No model.)

To all whom it may concern:

Be it known that we, WILLIAM J. HULFORD and FREDERICK TILLOTSON, both of Lawrence, in the county of Essex, State of Massachusetts, have invented a certain new and useful Improvement in Picker-Staff Checks for Looms, of which the following is a description sufficiently full, clear, and exact to enable any person skilled in the art or science to 5 10 15 20 25 30 35 40 45 50 55 60 65 70 75 80 85 90 95 100 which said invention appertains to make and use the same, reference being had to the accompanying drawings, forming part of this specification, in which—

Figure 1 is a side elevation showing our improved picker-staff check in position for use on the lay of a loom, the picker-staffs and certain parts of the loom being represented as broken off or removed; Fig. 2, a bottom plan view showing the check as applied to the lay, the picker-staff being represented in cross-section and the lay detached from the loom and broken off; Fig. 3, a view of the check detached, the spring being represented in cross-section and the tension-slide in side elevation; 25 and Fig. 4, a diagram showing the arrangement of the check with reference to the picker-staff.

Like letters of reference indicate corresponding parts in the different figures of the 30 drawings.

Our invention relates to that class of picker-staff checks which are attached to the lay of the loom; and it consists in a novel construction and arrangement of parts, as hereinafter 35 more fully set forth and claimed, the object being to produce a simpler, cheaper, and more effective device of this character than is now in ordinary use.

The nature and operation of the improvement will be readily understood by all conversant with such matters from the following 40 explanation.

In the drawings, A represents the picker-staff, B the picker, and C the lay of the loom, 45 these parts being all of the ordinary form and construction.

A long flat steel spring, D, has one of its ends rigidly secured by a screw, x, to the under side of the lay, near each end thereof, the 50 free ends of said springs respectively pro-

jecting outward or toward the ends of the lay, as shown in Fig. 1. The springs are slightly curved laterally and are arranged edgewise on the lay, each being so disposed that its body projects into the path m of the corresponding picker-staff, as best shown in Fig. 4, in which said staff and the slot or path in which it moves back and forth are indicated by dotted lines. A tension-slide, E, is provided for regulating the tension of each of the springs 55 D. The slides are respectively composed of a single piece of wire bent to form the elongated body or loop z, as shown in Fig. 2, and downwardly-projecting U-shaped bracket f, and are secured to the under side of the lay by 60 screws r, which pass through the loops z, the free ends of the springs D resting in the brackets f. By loosening the screws r and moving the slides more or less laterally of the lay the springs D will be projected more or 65 less into the paths of the picker-staffs, whereby the tension or pressure of the springs on the staffs is regulated. When the slides are adjusted to secure the desired tension, the screws 70 are again tightened.

From the foregoing it will be obvious that when the shuttle is thrown and comes into contact with the picker B on the staff A said staff will be forced against the spring D, striking 75 said spring in the vicinity of the point v and 80 forcing it back out of the path m, thereby gradually retarding the speed of the shuttle until it arrives at the end of its race, thus enabling a very loose shuttle-box to be employed, obviating to great extent the necessity of 85 binders, and reducing the wear on the shuttle.

It will be observed by reference to Fig. 4 of the drawings that the spring D projects into the path m of the shuttle to the greatest extent at or near its center or at the point d, from 90 which point to the end of said path at y the spring is slightly inclined laterally and outward, so that when the staff has arrived at y it will be securely held or prevented from rebounding and throwing the shuttle back in 95 the race, thus utilizing the full length of the box or race at each pick, and securing better results than are possible where the vibratory movements of the upper end of the picker-staff are not gradually retarded and the vibra- 100

tory movements of its upper end controlled, as described.

A round spring, D, may also be employed instead of a flat one, if desired, although we deem the flat one preferable, as it presents a larger surface to the action of the picker-staff and does not wear it away so rapidly as a round spring.

Having thus explained our invention, what we claim is—

1. The tension-slide E, having the body or loop z, provided with the bracket f, in combination with the spring D, picker-staff A, lay C, and screws x r, said spring being bent or curved laterally, as shown at d, and all arranged to operate substantially as described.
2. The tension-slide E, having the body or

loop z, provided with the U-shaped bracket f, said body and bracket being integral, or composed of a single piece of wire, and a screw 20 for adjustably securing said slide to the lay C, in combination with the picker-staff A and flat steel spring D, bent or curved laterally at its center, as shown at d, and the screw x, for securing said spring to the lay, the free end 25 of said spring being inserted in the bracket f of said slide, and all constructed and arranged to operate substantially as and for the purpose shown and described.

WILLIAM J. HULFORD.
FREDERICK TILLOTSON.
